UNITED STATES PATENT OFFICE.

JESSE D. HEDRICK, OF MARION, INDIANA.

COIN SORTER.

Application filed February 13, 1924. Serial No. 692,489.

To all whom it may concern:

Be it known that I, JESSE D. HEDRICK, a citizen of the United States, residing at Marion, in the county of Grant and State 5 of Indiana, have invented certain new and useful Improvements in Coin Sorters, of which the following is a specification.

This invention relates to machines for sorting coins or the like, of that type in 10 which the mixed coins are allowed to flow down a chute which is provided with selective devices for dropping the coins respectively, according to different denominations, thru different openings and into different 15 receptacles. Associated with this structure is a feeding mechanism for feeding the coins one by one into the upper end of the chute, said feeding mechanism comprising a rotary cup having openings thru which the coins 20 are discharged one by one into the top of the chute.

In the present invention, the coins slide down the chute flatwise, and on reaching the baffles or separating devices are lifted 25 and tipped over sidewise into an opening at the side of the chute through which they fall into a box or receiving device below.

The invention will be more fully understood from the following description and the 30 accompanying drawings in which Fig. 1 is a side elevation of the device. Fig. 2 is an end elevation. Fig. 3 is a detail in perspective of a section of the chute. Fig. 4 is a detail in section of the feeder. Fig. 5 is a section 35 on the line 5—5 of Fig. 1.

Referring specifically to the drawings, 6 indicates a base on which is mounted a standard 7 which supports the upper end of the chute 8 and the feeder at the top thereof, the lower end of the chute being supported by leg 9, and the chute extending at 40 rather an acute angle downwardly from the upper to the lower end.

The feeder comprises a hopper 10 having 45 an outlet 11 at the bottom thereof to the chute 8. Within this hopper is mounted a rotary cup 12, on a shaft 13 which extends thru the bottom wall of the hopper and is provided with a crank handle 14 whereby it 50 may be turned, the upper end of the shaft being supported by an angular bracket 15 secured to the hopper. By turning the crank, the cup may be rotated in the hopper, and the lower edge or corner of the cup 55 is provided with a plurality of slots 16 thru which the coins may or will drop one at a

time when they reach the space or position opposite the spout 11, thru which they slide to the chute. The slots 16 are sufficiently large to allow the passage of the largest coin 60 to be sorted, larger coins if any being retained in the cup.

The chute may be made of sheet metal, and at one side it has a track or slideway 17 with a flange or wall 18 at one edge thereof, this flange having a series of openings 19 which are progressively smaller in size toward the lower end of the chute. The bottom of the slideway 17 is slightly inclined sidewise toward the flange 18 so that the 70 coins have some tendency to hug the flange 18 as they slide down. The opposite edge of the slideway 17 has a series of separating devices or baffles 20 each of which consists of a curved piece of metal the upper edge of 75 which, indicated at 21, has somewhat the form of a spiral, and the upper end of which edge, as indicated at 22, merges into or rises from the floor of the slideway 17, and thence the edge curves over the slideway and leads 80 at its lower end to one of the openings 19 which communicate with openings 23 thru which the coins may drop into drawers or receptacles 24 placed under the chute to receive the coins. Also, at the lower end of 85 each opening 19 is a pointed finger 25 which is offset from the flange 18 inwardly and partly across the slideway 17, the finger however being spaced above the floor of the slideway so that a coin which is not engaged 90 by the baffle 20 will slide under said finger and also under said baffle and thence down the slideway to the next baffle, and so on.

The operation is as follows: Assuming 95 that a mass of coins is placed in the cup 12, the cup is rotated by the crank, and the coins escape one by one thru the slot 16, being actuated by the inclination of the bottom of the cup as well as by the centrifugal force developed. They then slide thru the spout or 100 throat 11 onto the slideway 17. Assuming that the device is intended to sort quarters, nickels, pennies, and dimes, the quarters, or the coins of the largest size, are of such diameter that one edge thereof will ride up the spiral edge 21 of the baffle 20 and will thereby be tilted to a standing position and being guided by the edge 21 will roll out of the chute sidewise and thru the opening 19 adjacent thereto. The finger 25 by engaging 105 in front of or under the coin will prevent the coin being cocked or upsetting and so

continuing down the slideway. A coin of a smaller size, say a nickel, will however not be engaged by the edge 22 of the first baffle, but will continue to slide down the 5 slideway, passing under the finger 25 and the baffle 20, until it reaches the next baffle, the entering end 22^a of which is set closer to wall 18, so that the nickel will ride up said edge and will in a manner similar to that 10 above described be tilted up and discharged thru the next opening 19. The pennies will pass the two upper baffles, and the dimes will finally be delivered from the lower end of the chute into a drawer or receptacle such as 24^a. So by a series of spirally formed baffles, with each of which is associated a finger, the baffle extending across and the finger projecting above the slideway, the 15 coins are assorted according to their respective denominations and are tilted from a flat position to an edgewise position and discharged thru openings at the side of the chute into appropriate receptacles. The pitch of the spiral edges 21 is such that 20 gravity will nevertheless cause the coins to tilt to the upright position described and roll out at the side.

The device can be quite cheaply constructed of sheet metal and will effectively 30 perform the functions described. Obviously the feeder may be omitted and the coins fed into the machine by hand, one by one, but the feeder provides means for rapid operation, the coins being placed in a mass or 35 handful into the cup as the operation proceeds.

The invention is not limited to the particular form shown but may be embodied in various modifications thereof.

40 I claim:

1. In a coin sorter in combination, an inclined chute having a slideway at one side thereof down which coins slide flatwise and a flange provided with openings at the inner 45 edge of the slideway, and a series of baffles adjacent the openings successively, each baf-

fle consisting of a curved member having a spiral upper edge extending over the slideway at a sufficient height above the same to tilt the coins to edgewise position, the 50 upper end of said edge rising from the floor of the slideway, whereby coins will ride up said edge and be tilted thru the openings, the said upper ends of the successive baffles being positioned at decreasing distances 55 from said flange.

2. A coin sorter as set forth in claim 1, and a finger projecting from said flange, at the lower end of the opening therein, above the slideway and under the respective baffle, said finger being spaced above the slideway.

3. A feeder for a coin sorting machine, comprising a hopper, and a rotary cup therein, said cup having openings in the lower 65 corner thereof, thru which coins may be discharged into the hopper.

4. A feeder as set forth in claim 3, the axis of said cup being inclined.

5. A feeder as set forth in claim 3, the 70 bottom of the hopper being inclined and having an outlet spout at the lower corner thereof.

6. A coin sorter comprising a chute having an inclined slideway at one side thereof 75 down which coins slide flatwise and a series of openings beside the slideway, and a series of baffles about the chute, each baffle consisting of a spiral member rising from the outer edge of the slideway and curving sufficiently high above the slideway to tilt the coins to edgewise position, and terminating at the opposite edge of the slideway, adjacent one of said openings, the upper ends 80 of the successive spirals being spaced at decreasing distances from the inner edge of the slideway.

In testimony whereof, I affix my signature in presence of a witness.

JESSE D. HEDRICK.

Witness:

E. F. FERREE.
